UNITED STATES PATENT OFFICE

MAX AMIEL, OF ST. PETERSBURG, FLORIDA, ASSIGNOR TO CONGOLEUM-NAIRN INC.,
OF KEARNY, NEW JERSEY, A CORPORATION OF NEW YORK

DESIGN FOR LINOLEUM OR SIMILAR HARD-SURFACE FLOOR COVERING

Application filed January 30, 1931. Serial No. 38,485. Term of patent 7 years.

To all whom it may concern:

Be it known that I, MAX AMIEL, a citizen of the United States, residing at St. Petersburg, in the county of Pinellas and State of Florida, have invented a certain new, original, and ornamental Design for Linoleum or Similar Hard-Surface Floor Covering, of which the following is a specification, reference being had to the accompanying drawing, forming a part hereof.

The drawing represents a plan view of a section of linoleum or similar hard surface floor covering showing my new design, a unit of the design being illustrated in the area bounded by the dot and dash lines A—A', B—B', C—C' and D—D', and said unit being repeated continuously, in the manner indicated, throughout the area of the floor covering.

I claim:

The ornamental design for linoleum or similar hard-surface floor covering substantially as shown and described.

In testimony whereof, I affix my signature.

MAX AMIEL.
